UNITED STATES PATENT OFFICE.

WILLIAM F. EHMANN, OF BUFFALO, NEW YORK.

DESIGN FOR A SPOON.

SPECIFICATION forming part of Design No. 34,469, dated May 7, 1901.

Application filed March 19, 1901. Serial No. 51,945. Term of patent 7 years.

To all whom it may concern:

Be it known that I, WILLIAM F. EHMANN, a citizen of the United States, residing at the city of Buffalo, in the county of Erie and State 5 of New York, have invented and produced a new and original Design for Spoons, of which the following is a specification, reference being had to the accompanying drawing, forming a part thereof.

10 This design relates to the shape or configuration and the ornamentation of a spoon or similar article.

The accompanying drawing is a face view of a spoon embodying my design.

15 The leading or characteristic feature of my design consists of the figure A of a nude female occupying the greater portion of the spoon-handle, and the figure B of an animal's head arranged upon the oval or widened outer 20 end of the spoon-handle and represented as being held aloft by the female figure.

As shown in the drawing, the edges of the spoon-handle are curved irregularly and follow the outline of the female figure A.

c represents rococo ornaments arranged 25 upon the widened portion of the spoon-handle around the figure B of the animal's head.

d is a bow or ribbon arranged at the top of the spoon-bowl E, and f represents sprays of flowers or foliage represented as springing 30 from the bow d and running along opposite edges of the bowl.

What I claim is—

The design for a spoon or similar article, substantially as herein shown and described. 35

Witness my hand this 16th day of March, 1901.

WILLIAM F. EHMANN.
